UNITED STATES PATENT OFFICE.

EDWIN E. MILNER, OF SCOTT TOWNSHIP, ALLEGHENY COUNTY, AND WILLIAM J. LYTTLE, OF ROSSLYN FARMS BOROUGH, PENNSYLVANIA, ASSIGNEES TO H. L. DIXON COMPANY, OF PITTSBURGH, PENNSYLVANIA, A CORPORATION OF PENNSYLVANIA.

PLATE-GLASS-ANNEALING LEER.

Application filed June 15, 1921. Serial No. 477,619.

To all whom it may concern:

Be it known that we, EDWIN E. MILNER and WILLIAM J. LYTTLE, citizens of the United States, residing, respectively, in

5 Scott Township and Rosslyn Farms Borough, both in the county of Allegheny and State of Pennsylvania, have invented a new and useful Improvement in Plate-Glass-Annealing Leers, of which the following is a 10 full, clear, and exact description, reference being had to the accompanying drawings, forming part of this specification, in which—

Figure 1 is a longitudinal vertical section of a portion of a plate glass annealing 15 leer embodying our invention, the plane of section being on the line I—I of Figure 2; and

20 Figure 2 is a section on the line II—II of Figure 1.

Our invention has relation to plate glass 25 annealing leers, and is designed to provide a muffle type of leer having effective means for producing and maintaining the proper temperature within the muffle chamber. The invention also provides a muffle leer in which the oven portion of the leer can be arranged in a straight line with the leer end.

The particular nature of our invention 30 will be best understood by reference to the accompanying drawings, in which we have shown a preferred embodiment thereof and which will now be described, it being pre- 35 mised, however, that various changes may be made in the details of construction, arrangement and combination of the various parts without departing from the spirit and scope of our invention as defined by the ap- 40 pended claims.

In these drawings, the numeral 2 designates the frame of the leer and 3 the outer masonry walls thereof. 4 is the muffle chamber into the rear end portion of which the glass plates to be annealed are introduced 45 through a lateral opening, such as shown at 5 in Figure 1. 6 is the usual refractory bottom of the muffle chamber. The top wall of the muffle chamber is composed mainly of a plurality of longitudinally extending flues 50 7, these flues being arranged side by side and extending substantially the full length of the chamber. They may be conveniently formed of hollow tiles, either of integral construction or built up of separate top and

side members, as indicated in Figure 2. 55 They are shown as being supported by means of the I-shaped key blocks 8, which are in turn suspended from the longitudinal channels 9, these channels being in turn suspended from the transverse frame beams 10. 60 The top walls of the flues 7 may be reinforced by a layer 11 of bricks or other refractory material set between the key blocks.

At its rear end each of the flues 7 com- 65 municates with a vertical combustion cham- 70 ber 12 which extends upwardly through the rear end wall of the muffle chamber. There is one of these combustion chambers for each of the longitudinal flues. Each combustion chamber is provided with a suitable burner 75 arrangement. In the construction shown in the drawings, the leer is arranged to be fired either by producer gas or by natural gas. When producer gas is used, the gas is brought in through the flue or tunnel 13. 80 This flue has a series of openings 14 in its top wall, one for each combustion chamber, and opening into a box 15 which discharges into the lower portion of the combustion chamber. Air enters the lower portion of 85 the combustion chamber through an opening 16 which is controlled by a suitable valve or damper 17. This valve or damper is shown as being of the sliding type, and is arranged to be moved by the hollow rod or stem 18 90 having a hand wheel 19. The valve 17 is made hollow and is provided with an escape orifice at its upper end, adapted to constitute a burner when natural gas is employed as the fuel. In that case, the gas is supplied through a flexible pipe 20 which is connected to the end of the hollow valve rod or stem 18. The gas discharged into each com- 95 bustion chamber is controlled by any suit- 100 able valve, such as the swinging valve 21, carried by the rock shaft 22 having the actu- 105 ating connection 23 for manual operation. When natural gas is employed, the valve 21 is closed and the supply of natural gas reg- 110 ulated by a suitable valve 24 in the supply pipe 20.

It will be understood that each of the com- 115 bustion chambers is supplied with its own individual burner and with its own gas and air supply connection so that the combustion in each chamber may be independently regulated.

Each of the flues 7 is provided with a plu-

rality of vertical off-takes 25 at different points in its length. These off-takes communicate with a series of transverse flues 26 which, in turn, open into a longitudinal pipe or flue 27 leading to the stack 28. Each of the connections 25 has a control valve or damper 29.

In the particular leer illustrated in the drawings, there are twelve of the longitudinal flues 7, and each of these flues is provided with four off-take connections 25. It will be understood, however, that the number of flues may be widely varied, according to the size of the leer, and that more or less off-take connections may be provided for each flue. The valves or dampers 29 of each set of off-take connections are preferably operated as a unit by any suitable means, such as indicated at the upper right-hand portion of Figure 2, in which a number of one set of these valves are shown as having connections 30 to a rock shaft 31 which may be operated in any suitable manner (not shown) for the purpose of moving the valves of that set in unison. It will be understood that each of the four transverse sets of valves may be operated in unison in a similar or in any suitable manner.

By the provision of the plurality of off-take connections, the temperature of different portions of the muffle chamber may be accurately regulated as desired.

The leer end portion of the leer may be of any usual or suitable construction, the glass plates to be annealed being pushed or conveyed through the muffle and into the lower end in any suitable manner and by any suitable means, forming no part of the present invention.

40 The advantages of our invention result from the provision of a muffle chamber whose upper wall is formed by a series of heating flues, together with means for regulating the heating action of the flues. The construction is a simple and comparatively inexpensive one, no heating chamber or heating flues being required at the sides of the muffle.

We claim:

1. A plate glass annealing leer having a muffle chamber whose upper wall contains a plurality of longitudinally extending heating flues, and means in each of said flues for producing combustion therein, substantially as described.

55 2. A plate glass annealing leer having a muffle chamber whose upper wall contains a plurality of longitudinally extending heating flues, together with a separate combustion chamber for each of said flues, substantially as described.

60 3. A plate glass annealing leer having a muffle chamber whose upper wall contains a plurality of longitudinally extending heating flues, together with a separate combustion chamber for each of said flues, and

means for producing combustion in each of said chambers, substantially as described.

4. A plate glass annealing leer having a muffle chamber whose upper wall contains a plurality of longitudinally extending heating flues, each of said flues having a plurality of off-take connections extending from different points of its length, substantially as described.

70 5. A plate glass annealing leer having a muffle chamber whose upper wall contains a plurality of longitudinally extending heating flues, each of said flues having a plurality of off-take connections extending from different points of its length, and each of said connections having valve or damper means, substantially as described.

80 6. A plate glass annealing leer having a muffle chamber whose top wall contains a plurality of longitudinally extending heating flues arranged side by side, each of said heating flues having a plurality of off-take connections at different points in its length, a series of transverse flues into which said connections lead, and a stack flue into which the transverse flues discharge, substantially as described.

85 7. A plate glass annealing leer having a muffle chamber whose top wall contains a plurality of longitudinally extending heating flues arranged side by side, each of said heating flues having a plurality of off-take connections at different points in its length, a series of transverse flues into which said connections lead, and a stack flue into which the transverse flues discharge, each of the off-take connections having a controlling valve or damper, substantially as described.

90 8. A plate glass annealing leer having a muffle chamber whose top wall contains a plurality of longitudinally extending heating flues arranged side by side, each of said heating flues having a plurality of off-take connections at different points in its length, a series of transverse flues into which said connections lead, and a stack flue into which the transverse flues discharge, each of the off-take connections having a controlling valve or damper, said dampers being arranged in sets, and means for separately operating the dampers of each set, substantially as described.

95 9. A plate glass annealing leer having a muffle chamber at the oven end and a leer end in line with the muffle chamber and communicating therewith, the top wall of the muffle chamber having therein a plurality of longitudinally extending heating flues, substantially as described.

100 10. A plate glass annealing leer having a muffle chamber at the oven end and a leer end in line with the muffle chamber and communicating therewith, the top wall of the muffle chamber having therein a plurality of longitudinally extending heat-

ing flues, together with separate heating means for each of said flues, substantially as described.

11. A plate glass annealing leer having a muffle chamber at the oven end and a leer end in line with the muffle chamber and communicating therewith, the top wall of the muffle chamber having therein a plurality of longitudinally extending heating flues, together with separate heating means for each of said flues, and a plurality of controllable off-take connections to each of the heating flues, substantially as described.

12. A plate glass annealing leer having a muffle chamber whose top wall is provided with a plurality of heating flues and whose rear end wall has a plurality of combustion chambers each of which communicates with one of said flues, and means for producing combustion in each of said chambers, substantially as described.

13. A plate glass annealing leer having a muffle chamber whose top wall is provided with a plurality of heating flues and whose rear end wall has a plurality of combustion chambers each of which communicates with one of said flues, and means for producing combustion in each of said chambers, together with means for independently regulating the combustion in each chamber, substantially as described.

14. A plate glass annealing leer having a muffle chamber provided with a plurality of longitudinally extending heating flues at its upper portion, a separate combustion chamber for each of said flues, and means whereby each of said combustion chambers may be supplied with different kinds of fuel, substantially as described.

15. A plate glass annealing leer having a muffle chamber whose upper wall contains a series of longitudinally extending heating flues arranged side by side, means for suspending said flues from the frame of the furnace, and means in each of said flues for producing combustion therein, substantially as described.

16. A plate glass annealing leer having

a muffler whose upper wall contains a plurality of longitudinally extending heating flues, each of said flues being formed of tile members, key blocks suspending the tile members, means for suspending the key blocks from the frame of the furnace, and means in each of said flues for producing combustion therein, substantially as described.

17. An annealing leer having a muffle chamber at the oven end and a leer end in line with the muffle chamber and communicating therewith, the top wall of the muffle chamber having therein a plurality of longitudinally extending heating flues, substantially as described.

18. In a leer, a muffle chamber and a leer end adapted to have material move progressively therethrough through changing temperature zones, the top wall of the muffle chamber having therein a plurality of longitudinally extending heating flues, substantially as described.

19. An annealing leer having a muffle chamber at the oven end and a leer end in line with the muffle chamber and communicating therewith, the top wall of the muffle chamber having therein a plurality of longitudinally extending heating flues, at least one of the heating flues having means at different points in the length thereof for the offtake of products of combustion, substantially as described.

20. An annealing leer having a muffle chamber at the oven end and a leer end in line with the muffle chamber and communicating therewith, the top wall of the muffle chamber having therein a plurality of longitudinally extending heating flues, at least one of the heating flues having a damper controlled offtake leading therefrom to control the offtake of heating gases, substantially as described.

In testimony whereof, we have hereunto set our hands.

EDWIN E. MILNER.
WILLIAM J. LYTLE.
